UNITED STATES PATENT OFFICE.

NELSON M. BAKER, OF SOUTHBRIDGE, MASSACHUSETTS.

GUARD.

1,132,760.

Specification of Letters Patent.

Patented Mar. 23, 1915.

Application filed November 23, 1914. Serial No. 873,484.

To all whom it may concern:

Be it known that I, NELSON M. BAKER, a citizen of the United States, residing at Southbridge, in the county of Worcester 5 and State of Massachusetts, have invented certain new and useful Improvements in Guards, of which the following is a specification.

My invention relates to improvements in 10 guards for use on ophthalmic mountings, and has particular reference to an improved construction of guard, and further an improved method or process of securing the facing to the guard.

15 The leading object of my invention is the provision of an improved form of guard which may be so constructed as to eliminate the use of metal rivets, or the like, in securing the facing in position, and will thus 20 serve to prevent any metal from coming into contact with the face of the wearer.

A further object of my invention is the provision of an improved manner of securing together or connecting the back plate and 25 facing therefor so that the facing will be securely but simply attached without the use of separate attaching devices.

Other objects and advantages of my improved construction of guard and facing 30 therefor should be readily apparent by reference to the following description taken in connection with the accompanying drawings, and it will be understood that I may make any modifications in the specific 35 details of construction shown and described, or the specific steps in the securing of the facing to the back plate, within the scope of the appended claims without departing from or exceeding the spirit of my invention.

40 Figure I represents a view of a mounting equipped with my improved guard. Fig. II represents a face view of one form of my guard. Fig. III represents a similar view 45 of another form thereof. Fig. IV represents a sectional view on the line IV—IV of Fig. III. Fig. V represents a sectional view of another modified form of my construction. Fig. VI represents a similar sectional 50 view of another form thereof.

55 In the drawings, in which similar characters of reference denote corresponding parts throughout the several views, the numeral 1 designates the bridge of a mounting supporting the usual lenses 2, and provided

with suitable guards for retaining the mounting in correct position upon the face of the wearer. These guards I preferably form of a back plate 3 of metal or like material, having one or more apertures 4 60 formed therein.

Previous to my invention when it has been desired to place on the face of a metallic guard a facing or contacting portion 5 of zylonite shell or the like, it has been 65 necessary to make a special construction of blade 3, and provide the same with perforations to receive securing rivets. With my invention, however, this necessity for a special construction of guard is done away 70 with, in that I am able to satisfactorily secure the facing 5 to the blade 3 without the use of said rivets and without in anywise varying the structure of the blade itself. This result I attain by forming the facing 75 5 with a portion 6 projecting through the aperture 4 in the blade and with the expanded, headed or flaring portion 7 which engages the rear face of the blade 3 and thus serves to securely retain the facing 5 in position, as is clearly illustrated in the several views of the drawing.

In that form of my invention illustrated in Figs. II and III, I have shown the guard blade 3 provided with two apertures, in 85 Fig. II the material being continuous over the entire face of the blade, and in Fig. III being separate, making upper and lower nose contacting portions.

In Fig. V, I have shown a section taken at right angles to the view in Fig. IV, showing a slight modification of construction, in that in this instance the material in place of being sunken in the center to provide the flesh receiving recess 8 illustrated in 90 Fig. IV, the facing is slightly rounded and provided with corrugations to prevent slipping thereof.

In Fig. VI, I have illustrated a form particularly adapted for use as a holding pad, 100 in that the blade portion 3 consists merely of a small ring, the facing material fitting within the aperture 4 of the ring, and also curving slightly over the edge thereof to completely cover the same.

105 It is to be noted that in the several sectional views the manner of securing the facing in position is the same, that is to say, a portion of the facing is forced rearwardly through the aperture 4 in the blade, and is 110

then laterally deflected or expanded to bear against the rear face of the blade and thus retain the same in position.

In Fig. IV, I have shown the blade as cut square, while in Figs. V and VI it is illustrated as formed with the bevel 9, thus involving less projection of the material on the rear face of the blade.

In securing the pad in position I preferably subject the same to sufficient heat to satisfactorily soften the facing and then press the same against the blade, when a portion will be forced therethrough, it then being merely necessary to head or flatten out said rearwardly projecting portion to permanently unite the parts.

If preferred, the facing 5 may be suitably prepared before the heating for placing in position. That is to say, it may be shaped to desired configuration and rounded or indented, as indicated in the several views, and formed with a tang or rivet like portion on the rear face thereof, in this event it being merely necessary to press the tang through the aperture formed in the blade and to then, either from softening from previous

heating, or by heating as by a hot tool pressed thereagainst, or the like, to sufficiently soften said tang to permit of ready spreading thereof into interlocking relation with the blade.

I claim:

1. The process of facing a guard, consisting in forming a blank with an aperture, heating a facing therefor, forcing a portion of the facing while heated through the aperture, and laterally deflecting portions of the facing to secure it in position.

2. The process of facing a guard blade consisting in forming an aperture in the blade, pressing a portion of the facing through the aperture, heating the portion projecting through the aperture and spreading the portion so passed through the aperture while under the influence of heat to prevent its withdrawal when cooled.

In testimony whereof I affix my signature in presence of two witnesses.

NELSON M. BAKER.
